COOLING UNIT

Filed Nov. 22, 1930

INVENTOR:
WILLIAM SODEMANN.

Arthur C Eckert

UNITED STATES PATENT OFFICE

WILLIAM SODEMANN, OF ST. LOUIS, MISSOURI

COOLING UNIT

Application filed November 22, 1930. Serial No. 497,392.

The object of my invention is to make a cooling unit to be used in offices and homes. A more specific object is to make a cooling unit in the form of a fixture or a piece of furniture. A more specific object is to make a unit for cooling air in a room or enclosure. The air at room temperature is drawn into the fixture over cooling coils by means of a centrifugal fan and blown into the room in its cooled condition. By this means, the humidity in the air may be also controlled within certain limits. In the drawings a fixture known as a grandfather's clock is shown. Applicant does not desire to be limited to this form of fixture. This device may be incorporated in any other type of fixture used in the office or home, such as a desk, table, bookcase, etc.

The invention may be made of few and simple parts that lend themselves readily to multiple production, and may be easily installed in ordinary fixtures.

With these and other objects in view, my invention has relation to certain novel features of construction and arrangement of parts as will be hereinafter more fully described, pointed out in the claim and illustrated in the drawings in which

Fig. 1 is a side elevation partially in section.

Fig. 2 is a front elevation.

Fig. 3 is a sectional elevation taken on the line 3-3 of Fig. 1.

Numeral 4 designates the fixture generally, which may have the base 5, the front wall 6 and the rear wall 7, and the side walls 8. The base and the walls thus far described form an enclosure or cabinet 9. In the side walls 8 are positioned the perforated plates 10. Numeral 11 designates the top of the fixture, which has the beveled face 12 on the front portion and the beveled faces 13 on the side portions.

Numeral 14 designates the portion of the upper front face of the fixture. Numeral 15 designates a perforated plate positioned in the upper front face of the fixture. The front wall 6 has the set backs 16 and 17. The vertical wall portion 18 connects the inner ends of the set backs 16 and 17. Thus

for a cabinet of the configuration shown in the drawings has been described. Numerals 19 designate vertical pillars connected at their lower ends in the set backs 16 and at their upper ends in the set backs 17. These pillars 19 are simply for the purpose of ornamentation. In the vertical wall portion 18 a panel such as 20 may be formed. Numeral 21 designates a cooling coil secured in any conventional manner in the lower part of the cabinet 9. The pipe connections for the ingress and egress of the refrigerant are shown at 22 and 23. Numeral 24 designates an electric motor, which is secured in the upper portion of the fixture 4 by means of the brackets 25 and 26. The bracket 25 is secured to the rear wall 7 and the bracket 26 is secured to the beveled face 12. The motor is so positioned that its armature is in a vertical plane. Numeral 27 designates a centrifugal fan, which is secured to the free end of the armature of the electric motor 24, in such manner that it is immediately behind the perforated plate 15. Numeral 28 designates a frusto-conical element, secured to the rear wall 7 and the upper front face 14 and to the centrifugal fan 27. Numeral 29 designates a conical element secured to the rear wall 7 and the upper front face 14 below the centrifugal fan 27.

The upper and lower bases of the frusto-conical element 29 are open. The direction of travel of the air is shown by the arrows in Figs. 1 and 3. In operation the electric motor 24 is operated thereby rapidly rotating the centrifugal fan 27, which draws the air from beneath it into the center of the fan and expels it at its periphery out of the fixture through the perforated plate 15. This causes the air from the room in which the fixture is positioned to be drawn from the room near the floor through the perforated plates 10 over the cooling coils 21 and upwardly through the fixture in the direction of the arrows through the centrifugal fan 27, as previously described. In this manner a circulation of air is produced through the fixture. The air, as is seen, is taken at room temperature near the floor of the room, cooled by the cooling coil 21 and blown into the room

at the lower temperature through the perforated plate 15.

Naturally the lowering of the temperature of the air lowers its saturation point, so that if the temperature is lowered too greatly and blown into the room, the air reaching the room would be too humid and in extreme cases would precipitate moisture. This is not desirable. It may be desirable to increase the humidity of the air in the room, but not to such an extent.

Owing to the travel of the air from the cooling coil 21 upwardly to the centrifugal fan 27, its temperature is sufficiently raised, although a slight amount, so that when the air is blown through the perforated plate 15 its relative humidity is lowered proportionately. It is understood that the conical element 28 prevents the air from passing upwardly to the electric motor 24 and the frusto-conical element 29 prevents the air from striking the centrifugal fan 27 at any other point other than its middle.

The fixture is portable and may be positioned anywhere where the electric motor 24 may be operated and a refrigerant may be supplied to the cooling coil 21.

Numeral 30 designates a drip pan placed in the bottom of the base 5 to catch and hold the precipitated moisture that drops from the cooling coil 21. Numeral 31 designates a pipe and coils attached to the drip pan 30, so that the water accumulated in the drip pan 30 may be periodically drawn off.

35 What I claim is:

A cooling unit having a cabinet, a cooling coil positioned in said cabinet and means for the ingress and egress of a refrigerant to said cooling coil, perforated plates positioned in said cabinet, an electric motor secured in said fixture at a distance from said cooling coil, a centrifugal fan operatively connected to said electric motor, a perforated plate positioned in said fixture immediately in front of said centrifugal fan, a frusto-conical element secured in said fixture so as to limit the path of travel of air in said fixture to the central portion of said centrifugal fan.

45 In testimony whereof I affix my signature.
50 WILLIAM SODEMANN.
